DEODORANT BLOCK HOLDER

Arnold A. Koistinen, Rte. 1, Box 184,
Madison, S. Dak. 57042

Filed June 13, 1966, Ser. No. 2,652

Term of patent 14 years

(Cl. D16—2)

Fig. 1

Fig. 2

Fig. 3

The undisclosed rear portion of the holder is substantially plain.

I claim:

The ornamental design for a deodorant block holder, as shown and described.
